UNITED STATES PATENT OFFICE.

PAUL CRICCHIO, OF NEW YORK, N. Y., ASSIGNOR TO MAJESTIC LAMP WORKS, A PARTNERSHIP CONSISTING OF PHILIP SILBERHARTZ, JACOB SILBERHARTZ, AND HARRY SCHEINER, ALL OF BROOKLYN, NEW YORK.

DESIGN FOR A COLUMN FOR SMOKING STAND OR ARTICLE OF ANALOGOUS NATURE.

Application filed March 6, 1929. Serial No. 30,356. Term of patent 3½ years.

To all whom it may concern:

Be it known that I, PAUL CRICCHIO, a citizen of the United States, and a resident of New York, county of Bronx, and State of New York, have invented a new, original, and ornamental Design for a Column for Smoking Stand or Article of Analogous Nature, of which the following is a specification, reference being had to the drawing, forming a part thereof.

The single figure of the drawing shows a perspective view of the column for smoking stand or article of analogous nature.

I claim:

The ornamental design for a column for smoking stand or article of analogous nature substantially as shown.

PAUL CRICCHIO.
